UNITED STATES PATENT OFFICE

CHARLES A. MOSGROVE, OF WATERBURY, CONNECTICUT, ASSIGNOR TO THE AUTOYRE COMPANY, INC., OF OAKVILLE, CONNECTICUT, A CORPORATION OF CONNECTICUT

SLIDE BUCKLE

Application filed June 25, 1931. Serial No. 546,691.

This invention relates to new and useful improvements in slide buckles such as are used on the suspender straps of overalls and the like.

5 An object of the invention is to provide a buckle which may be easily and quickly positioned on a strap and secured thereon.

Another object is to provide a buckle which when positioned on a strap will not slip or casually change its position when the strap is pulled or tensioned.

A further object is to provide an improved buckle formed from a single piece of sheet metal.

15 Another object is to provide a buckle adapted to have a strap pass through it and including novel means to receive and secure an end of the strap to the buckle.

Other objects and advantages will become 20 apparent from a consideration of the following detailed description taken in connection with the accompanying drawing wherein the invention is shown. It is to be understood however, that the invention is not limited 25 to the details disclosed but includes all such modifications and variations as fall within the spirit of the invention and the scope of the appended claims to which claims reference is to be had for a definition of the invention.

In the drawing:

Fig. 1 is a front elevational view showing a portion of a strap and illustrating the 35 method of applying my improved buckle to the strap;

Fig. 2 is a front elevational view showing my improved buckle in position on a strap;

Fig. 3 is a sectional view taken substantially along the line 3—3 of Fig. 2;

Fig. 4 is a sectional view of the buckle alone, the view being taken substantially along the line 4—4 of Fig. 1;

Fig. 5 is a perspective view of the improved buckle;

Fig. 6 is a transverse sectional view of the buckle when closed the view being taken substantially along the line 6—6 of Fig. 5;

Fig. 7 is an elevational view showing a 50 slight modification; and

Fig. 8 is a sectional view along the line 8—8 of Fig. 7.

Referring in detail to the drawing the improved buckle generally designated 10 is shown as formed from a single piece of sheet metal and as including a substantially rectangular frame comprising longitudinal or side bars 11 and 12 and end bars 13 and 14 joining the side bars. The bars forming the frame are preferably pressed to be concavo-convex in cross section whereby to add rigidity to the frame.

Formed with one of the end bars or members, as for example with the end bar 13 is a cross member or central bar 15 extending 65 longitudinally of the frame of the buckle and in the direction of the end bar 14 of the frame. The cross member 15 is of general U-shape 70 in cross section and includes a connecting portion 16, side walls or arms 17 and lateral 75 longitudinally extending flanges 18. The flanges 18 are preferably continuations of the side or arm portions 17 and located at the free edges thereof.

Prior to the buckle being applied to a 80 strap the cross member 15 occupies a position relative to the frame 10 substantially as shown in Figs. 4 and 5 of the drawing. Here it will be noted that the cross member inclines outwardly away from the frame where- 85 by there is a space 19 between the free end of the cross member and the adjacent portions of the frame of the buckle.

At its free end the cross member 15 carries a pair of lugs 20, which lugs extend in the direction of the frame as clearly shown in Fig. 5. Extending inwardly from the end bar 14 of the frame is a lug 21. This lug is preferably formed with the frame as is the cross member 15 and during the forma- 90 tion of the cross member it is drawn slightly so as to dispose its free end over the lug 21 whereby on the cross member being pressed in the direction of the frame its free end will be disposed against the lug 21 so that the lugs 95 20 may be wrapped about the lug 21 as clearly shown in Fig. 6.

The portion 16 of the connecting member 15 has portions lanced and pressed therefrom to provide teeth or clamping members 22 each 100

connected at one end with the cross member. These teeth 22 are adapted to have the end of a strap inserted beneath them and the teeth will then be pressed in the direction 5 of the member 15 whereby to secure the ends of the strap to the member.

A strap 23 is indicated in Figs. 1, 2 and 3 and this strap may be a shoulder strap of a pair of overalls, usually formed of denim 10 similar to the material of the overalls, or the invention may be applied to other straps. In applying the invention to a strap the buckle is slipped on to a strap from the edge thereof by inserting the edge of the strap into 15 the space 19 between the frame and the cross member 15 as shown in Fig. 1. The strap may then be drawn into the buckle or the buckle may be drawn across the strap so as to dispose the edges of the strap beneath the 20 cross member 15.

After the edges of the strap are disposed within the frame, and as a matter of fact inwardly of the lugs 20 of the crossmember 15, the strap is doubled upon itself to form 25 a loop 24 which may support an eye 25 or other means for co-operating with a button. The end of the strap is then inserted beneath the teeth 22 and the entire assembly placed in a die. In the die the cross member 15 is 30 pressed in the direction of the frame to have its lugs 20 embrace the edges of the lug 21 on the frame and the said lugs 20 are wrapped about the lug 21 as shown in Fig. 6. During 35 this same operation the teeth 22 are forced in the direction of the cross member whereby to clamp the material of the strap against the cross member. Or if preferred, after 40 the strap is inserted under the central bar 15, or that is between it and the frame the free end of this bar may be pressed down into 45 the frame and secured by folding the lugs 20 around the opposite edges of lug 21 as shown in Fig. 6. This securely fastens the free end of the central bar to the frame and then the end of the strap may be clamped under the members 22 by a separate operation.

Attention is directed to the fact that the improved buckle may be easily and quickly applied to a strap and in connection with Fig. 5 it will be noted that the cross member 15 is so constructed that the longitudinally extending flanges 18 occupy a position somewhat to the rear of the frame when the cross member is secured by having its lugs 20 bent 55 about the lug 21. Therefore, there is considerable of an off-set in the strap 23 and the strap will not slip through the buckle on the strap being pulled. To adjust the buckle on the strap it is first necessary to draw the strap through one side of the buckle or beneath one of the side bars of the buckle and to then take up the slack by drawing the slack through the other side of the buckle. There is no casual or accidental slipping of 60 the buckle.

Figs. 7 and 8 show a slight modification of the buckle of the invention and in this form of the invention teeth 26 are pressed from the connecting portion 16 of the cross member 15. However, a certain amount of 70 material is removed as at 27 about the teeth and when the strap 23 is positioned beneath the teeth the teeth are pressed back into the plane of the portion 16 of a connecting member as clearly shown in Fig. 8, whereby portions 28 of a strap 23 are carried down inwardly of the outer surface of the connecting member and the end of the strap securely attached to the buckle.

Having thus set forth the nature of my 80 invention, what I claim is:

1. In a buckle, a frame, a cross member secured at one end to the frame and extending across the frame and having a free end, a projecting member on the frame and extending 85 toward the cross member, and means on one of said members adapted to engage the other of said members to secure the free end of the cross member to the frame.

2. In a buckle, a substantially rectangular 90 frame, a cross member secured at one end to a bar of the frame and extending across the frame and having its free end disposed adjacent the opposite bar of the frame, said cross member inclining relative to the frame 95 whereby to dispose its free end out of the plane of the frame to permit a strap to be slipped beneath the said free end into a position between the member and the frame, a projecting member on the said opposite bar 100 of the frame, said cross member adapted to be pressed in the direction of the frame to dispose its free end portion against said projecting member when a strap has been slipped between the cross member and frame, and lugs on one of said members and adapted to be bent against the other thereof to secure the 105 free end of the cross member to the frame.

3. In a buckle, a frame, a cross member secured at one end to the frame and extending across the same, said cross member inclining relative to the frame whereby to dispose its free end out of the plane of the frame to permit a strap to be slipped edgewise between the member and frame, a projection on the frame and extending toward the cross member, said cross member adapted to be pressed in the direction of the frame to dispose its free end portion against said projection when a strap has been slipped between the cross member and the frame, and lugs on the said free end portion of the cross member and adapted to be bent against the projection to secure the end of the cross member to the projection.

4. In a buckle, a frame, a cross bar integral 125 at one end with the frame and extending across the same, said cross member bendable into and out of the plane of the frame and adapted to occupy a position inclined relative to the same whereby to dispose its free 130

- end out of the plane of the frame to permit a strap to be inserted edgewise between the member and frame, said cross member adapted to be bent in the direction of the frame 5 after a strap has been slipped between the cross member and frame whereby to secure the strap in position with the cross member disposed substantially in the plane of the frame, means to secure the cross member in 10 the last named position, and longitudinally extending flanges on the cross member to engage the strap and off-set the same through the frame whereby to prevent slipping of the strap relative to the buckle.
- 15 5. In a buckle, a frame, a cross member secured at one end to the frame and extending at an incline across the frame and having a free end disposed out of the plane of the frame, said cross member adapted to be 20 pressed substantially into the plane of the frame, co-operating means between the member and frame for securing the member in the last named position, teeth-like portions lanced and pressed from the cross-member, 25 and said teeth-like portions adapted to be bent into engagement with the end portion of a strap to secure said end portion to the cross member.
6. In a buckle, a substantially rectangular frame, a cross member secured at one end to a bar of the frame and extending across the frame and having its free end disposed adjacent the opposite bar of the frame, said cross member inclining relative to the frame 30 35 whereby to dispose its free end out of the plane of the frame to permit a strap to be slipped beneath the said free end into a position between the member and frame, a projecting member on the said opposite bar of the frame, said cross member adapted to be 40 pressed in the direction of the frame to dispose its free end portion against said projecting member when a strap has been slipped between the cross member and frame, lugs on 45 one of said members and adapted to be bent against the other thereof to secure the free end of the cross member to the frame, and longitudinally extending flanges on the cross member to engage the strap and off-set the same 50 through the frame whereby to prevent slipping of the strap relative to the buckle.
- 55 7. In a buckle, a frame, a cross member secured at one end to the frame and extending across the same, said cross member inclined relative to the frame whereby to dispose its free end out of the plane of the frame to permit a strap to be slipped edgewise between the member and frame, said cross member adapted to be pressed in the direction of 60 the frame to engage the strap, and means on the free end portion of the cross member and adapted to co-operate with the frame to secure the said end of the cross member to the frame.
- 65 8. In a buckle, a substantially rectangular sheet metal frame, the bars forming said frame being convexed to render the frame rigid, a cross bar integral at one end with a bar of the frame and extending across the frame, said cross member bendable into and 70 out of the plane of the frame and before being applied to a strap normally occupying a position inclined relative to the frame whereby the free end of the cross member is disposed out of the plane of the frame to permit 75 a strap to be inserted edgewise between the member and frame, said cross member adapted to be bent in the direction of the frame after a strap has been inserted between the cross member and frame whereby to secure 80 the strap in position with the cross member disposed substantially in the plane of the frame, and means to secure the cross member in the last named position.
9. In a buckle, a substantially rectangular frame, a cross member secured at one end to a bar of the frame and extending across the frame and having its free end disposed adjacent the opposite bar of the frame, said cross member inclining relative to the frame 85 whereby to dispose its free end out of the plane of the frame to permit a strap to be inserted beneath said free end into a position between the member and frame, a projecting member on the said opposite bar of the frame, said cross member adapted to be 90 pressed in the direction of the frame to dispose its free end portion against said projecting member when a strap has been slipped between the cross member and the frame, lugs 95 on one of said members and adapted to be bent against the other thereof to secure the free end of the cross member to the frame, said cross member substantially U-shaped in 100 cross section, and said cross member including a flange extending from each of its arms to engage the strap and off-set the same through the frame whereby to prevent slipping of the strap relative to the buckle.
10. In a buckle, a frame, a cross member secured at one end to the frame and extending at an incline across the same and having a free end disposed out of the plane of the frame, said cross member adapted to be pressed substantially into the plane of the frame on a 110 strap being inserted between the cross member and frame, co-operating means between the member and frame for securing the member in the last named position, teeth-like portions lanced and pressed from said cross 115 member, and said teeth-like portions adapted to be bent into engagement with the end portion of a strap to secure said end portion to the cross member.
11. In a slide buckle, a substantially rectangular frame, a cross member secured at one end to a bar of the frame and extending across the frame and having its free end disposed adjacent the opposite bar of the frame, said cross member inclining relative to the 120 125 frame,

frame whereby to dispose its free end out of the plane of the frame to permit a strap to be inserted edgewise between the member and frame, a projection on the said opposite bar 5 of the frame and extending toward the cross member, said cross member adapted to be pressed in the direction of the frame to dispose its free end portion against said projection when a strap has been inserted between 10 the cross member and frame, lugs on the said free end portion of the cross member and adapted to be bent against the projection to secure the said end of the cross member to the projection, means on one side of the cross 15 member to secure the end of a strap thereto, and longitudinally extending flanges at the opposite side of the cross member to engage a strap and off-set the same through the frame to prevent slipping of the strap relative to the buckle.

12. In a buckle, a frame, a cross member secured at one end to the frame and extending at an incline across the same and having a free end disposed out of the plane of the 20 frame, said cross member adapted to be pressed substantially into the plane of the frame on a strap being inserted between the cross member and frame, co-operating means between the member and frame for securing 25 the member in the last named position, said cross member having openings therein, and teeth like portions lanced and pressed from the bar and adapted to be displaced toward said opening to depress portions of the material of a strap into said openings whereby 30 to secure the end of a strap to the buckle.

13. In a buckle, a frame comprising side 35 members and connecting end members, a central bar connecting the end members between the side member, said central bar being substantially U-shape in cross section and having laterally extending flanges on the edges of the sides of said U-shaped bar co-operating with the side members to place 40 bends in a strap to prevent sliding of the buckle thereon.

14. In a buckle, a sheet metal frame comprising side bars and connecting end bars, a central bar connecting the end bars between 45 the side bars and of substantially U-shape in cross section, laterally extending flanges on the sides of the central bar cooperating with the side bars to place bends in a strap to prevent the buckle sliding thereon, and means on the central bar to secure a free 50 end of the strap thereto.

In testimony whereof I affix my signature.
CHARLES A. MOSGROVE.
